[57] CLAIM

The ornamental design for a combined separator, strainer and measuring cup, as shown and described.

DESCRIPTION

FIG. 1 is a perspective view of a combined separator, strainer and measuring cup showing my new design.

FIG. 2 is a top plan view thereof.

FIG. 3 is a side elevational view thereof.

FIG. 4 is a front elevational view thereof.

FIG. 5 is a bottom plan view thereof.

FIG. 6 is a back elevational view thereof.

FIG. 7 is a sectional view thereof along line 7—7 in FIG. 2.

FIG. 8 is a perspective view of optional inserts.

FIG. 9 is a perspective view of the optional inserts showing the side not visible in FIG. 8.

Fig. 1.

Fig. 2.

Fig. 3.

Fig. 4.

Fig. 5.

Fig. 7.
